DESIGN FOR A BELT

Stanley Barbara, Bronx, N. Y.

Application April 8, 1942, Serial No. 106,495

Term of patent 7 years

To all whom it may concern:

Be it known that I, Stanley Barbara, a citizen of the United States of America, residing at the Bronx, county of the Bronx, State of New York, have invented a new, original, and ornamental Design for a Belt, of which the following is a specification, reference being made to the accompanying drawing, forming a part thereof.

The drawing shows a perspective view of the belt in closed and stretched condition, showing my new design.

The characteristic features of my design reside in a braided cord belt of the configuration shown, having leather closure straps and buckle parts, the respective ends of said braided cords being secured to said leather straps by sleeves and links, all as shown.

I claim:

The ornamental design for a belt, substantially as shown and described.

STANLEY BARBARA.
